METHOD AND APPARATUS FOR PRESSING,
DEAERATING, AND DRYING

Charles W. Williams, Louisville, Ky.

Application May 25, 1942, Serial No. 444,340

1 Claim. (Cl. 41—33)

This invention relates to methods and apparatus for pressing, de-aerating and drying in photographic procedures, and more particularly to methods and apparatus for use in tri-color pigment printing.

For the purpose of illustration, the invention will be described in connection with its specific application to the so-called carbro process.

In the preparation of colored prints by the tri-color pigment printing process or the carbro process, three color separation negatives are obtained by exposing three different plates on the same subject, each plate being exposed through a standard color filter, i. e. red, yellow or blue. A black and white print is made from each of the negatives on bromide paper. The bromide prints are contacted with so-called carbon tissues (red, yellow and blue) which have pigmented gelatin on their surfaces. In each case the bromide print, in conjunction with a sensitizer previously soaked into the pigmented gelatin, acts to form a hardened image on the colored gelatin which is identical to the image on the bromide print. The bromide print is removed from the pigment tissue and the latter pressed onto a sheet of smooth plastic material on which it is washed in hot water to remove the soft gelatin, leaving the hardened image. After the three colored images have been thus secured on three plastic sheets, they are transferred individually to a single temporary supporting sheet in registry and subsequently to a sheet of paper to make the final print.

In the step of applying the pigment tissue to the sheet of plastic, considerable difficulty has been encountered and much time has been wasted due to the inclusion of air bubbles between the contacting surfaces of the sheets, and air apparently included in the gelatin layer, and the necessity for removing these air bubbles. The existence of the air bubbles or pockets becomes particularly noticeable when the pigment sheets are immersed in warm water, as is necessary in the processing, because of the expansion of the air under the increased temperature. If the air bubbles are not removed, they cause imperfections in the final print.

Heretofore it has been the practice to squeegee the plastic sheet and the pigment sheet vigorously for an extended period of time in an effort to remove the air bubbles visible at this stage of the process. This causes the pigment sheet to stretch varying amounts in different directions so that it is difficult and sometimes impossible to secure later the exact registration of the three pigment sheets that is required in the finished print. The

time involved not only represents waste but as the time required for squeegeeing the three different gelatin prints may be different, the time control of the processing of the three prints is entirely disrupted and is reflected in the final print.

The application of pressure in connection with this step in the process is highly important. While mechanical pressing means and weights, such as marble slabs, have been employed, they are not only difficult to handle but are also difficult to manipulate to secure the uniform pressure that is required for the best prints. Where marble slabs are used, two or three slabs about $\frac{1}{8}$ " thick are usually employed, the pressure obtained thereby being in the order of 0.3# per square inch. Even when perfectly plane surfaces are provided in the press and the pressure is applied with absolute uniformity, which is virtually impossible with the devices now in use, the best prints cannot be secured because of irregularities in the other elements making up the sandwich such as the plastic, the pigmented gelatin and the paper. Such irregularities cause unequal distribution of pressure to the extent that double the intended pressure may be applied in some spots and only one-half the pressure in other spots.

The drying of the prints at this stage is also important as it has been found that they must be brought to approximately a predetermined water content before they are washed, else the resultant images are not satisfactory.

Similar problems as to air bubbles, pressure, and drying arise in connection with the transfer of the three registered pigment sheets from the temporary support to the final support. Heretofore considerable time has been required for the vigorous squeegeeing necessary to remove the air bubbles and for the final drying and difficulty has been experienced in securing even an approximate uniform pressure.

In overcoming the aforesaid disadvantages, it is an object of my invention to provide novel methods and means wherein steps such as the foregoing can be carried out in a much shorter time than has been possible heretofore and with better results.

Still a further object of my invention is the provision of novel methods and means wherein the steps of removing the air bubbles, reducing the moisture content, and applying uniform pressure can be performed simultaneously in the above procedure and in similar processes with assurance as to the final results.

In the drawing:

Figure 1 is an exploded view of my invention as embodied in an arrangement for simultaneously de-aerating, drying and pressing a pigment print onto a sheet of plastic.

Figure 2 is a section taken through one end of the flexible blanket of my invention illustrating the ridge or dam which is provided to insure air-tight contact with the supporting base.

Figure 3 is a section through the vacuum connection to the flexible blanket.

Figure 4 is a partial section taken on the line 4-4 of Figure 5, illustrating the manner in which the flexible blanket embraces the edges of the sheets thereunder.

Figure 6 is a section of a modified table top wherein a groove is formed in the table top to receive the sealing dam on the blanket.

The present invention involves the use of a base member for supporting the prints which are to be pressed, dried and deaerated for transfer or like purposes, and a blanket or cover of flexible air-tight material such as soft rubber which is placed over the prints with its sides in contact with the base member. Vacuum is then applied to the underside of the blanket whereupon it is pressed onto the base plate around its edges, forming an air-tight seal around the edges of the prints and a vacuum around the prints. This vacuum reduces the moisture content, removes the air bubbles contained in and on the prints, and simultaneously causes the blanket to press upon the prints with a uniform high pressure over the entire area.

Referring to Figure 1, a suitable support such as a table 11 having a substantially plane smooth top surface 12 is provided. Taking the step of transferring a pigment print onto a sheet of plastic by way of illustration, a plastic sheet is shown at 13 and pigment print at 14, the pigmented gelatin being on the underside of the print. Plastic sheet 13 is contacted with pigment print 14, the two laid upon table 11 and a blanket 15 of flexible air-tight material such as soft rubber placed over the assembled sheets. Blanket 15 is provided with a ridge or dam 16 on its underside and adjacent its edges which is arranged to contact surface 12 of table 11 outside the area of the plastic sheet and the pigment print as shown in Figure 4 and provide a surrounding air-tight seal. To facilitate the forming of the seal, the top of table 11 may be formed with a shallow groove 12' (Fig. 6) of a configuration corresponding to that of dam 16 and into which the lower portion of the dam may be fitted when the unit is assembled.

To connect the underside of blanket 15 to a source of vacuum such as a conventional aspirator 21 arranged to be operated by city water pressure and a hose connection 22, the blanket is formed with a hole 15' bounded on the upper side of the blanket by a small flange 17' on one end of a connection 17 arranged to receive hose connection 22. A ring 20 of smaller inside diameter than the outside diameter of flange 17' is fitted over connection 17 and suitably sealed to the upper-side of blanket 15 by rubber cement as shown at 18. To prevent localization of the vacuum effective through connection 17 and the possible sealing of the inner end of hole 15', a sheet 19 of porous material such as cloth is applied to the underside of the blanket and cemented thereto only about its edges. It is preferred to extend the cloth or like porous material over the entire underside of the blanket within the boundaries

of dam 16 and seal it to the blanket around its edges only. The provision of such a porous member insures the access of vacuum to all parts of the surface immediately adjacent the blanket, despite the connection of the vacuum at only one point. In lieu of a porous material, the underside of the rubber blanket may be slightly roughened.

In operation, the assembly presents the appearance shown in Figure 5 wherein it will be noted that blanket 15 is drawn down around its edges so that it conforms closely to the outline of the underneath sheets. By reason of this conformation of the blanket, a channel 23 (Fig. 4) is formed around the periphery of the sheet of plastic and the pigment sheet so that the vacuum beneath the blanket is effective completely around the periphery of the contacted sheets. As blotters or similar porous sheets are usually placed between table 11 and sheet 13 as well as between blanket 15 and pigment print 14, the vacuum is effective through the porous sheets on all surfaces of the contacted plastic and pigment sheet, this being further assured by porous material 19. This vacuum not only tends to reduce the moisture to the correct amount for the subsequent washing and to remove the air bubbles but also operates to cause the blanket to press the print and plastic sheet together with uniform pressure over their entire areas. The pressure obtainable with the well-known aspirator and city water pressure will run at least 12 lbs. per square inch which is equal to a pile of marble about 10 feet high or a pile of steel about 42" high. Such pressure is obtainable with a vacuum of about 25" Hg. In some cases, it has been found possible to secure a vacuum of as high as 28" Hg. with the same means and consequently secure a higher pressure.

Where it has heretofore been necessary to squeegee the wet pigment sheet and sheet of plastic for a considerable period of time and subsequently dry to the requisite degree of dampness before washing by pressing the sheets between blotter sandwiches and applying pressure in the order of 0.2# to 0.3# per square inch (as is obtainable with three marble slabs of the type usually employed) or more, it is possible with the invention to eliminate squeegeeing except what is actually necessary to bring the pigment and plastic sheet into contact and simultaneously dry to the desired degree, de-aerate and press with the desired degree of pressure within the period of 10 minutes. As three pigment sheets must be treated in each processing, this results in a saving of time in excess of 45 minutes for this step alone. Moreover as all the sheets are given uniform treatment for the same period of time, uniform results are assured and there is no disruption of the time schedule. It has been found in practice that the present invention brings the water content down to the requisite degree of dampness for the subsequent washing with hot water and it is not necessary to guess at the water content of each pigment sheet as has heretofore been necessary.

In the later step in the process wherein the gelatin images are transferred from the temporary support to the final mount, heretofore it has required approximately 40 minutes and the application of the considerable pressure to secure a satisfactory transfer. With the treatment of the temporary support and the final support by the method of this invention and the application of vacuum of the order that can be obtained with city water pressure and a conventional aspirator,

i. e., 25" to 28" Hg., it has been found possible to cut this time down to 10 minutes and secure better results.

Thus in the tri-color pigment process for a single print, it has been found possible to save in excess of 1 hr. and 15 minutes in actual time in addition to the time and labor involved in the squeegeeing hitherto considered necessary in an attempt to remove the air bubbles, and the additional apparatus required to secure what was hoped to be the desired uniform pressure.

In the over-all process it has been found possible to save as much as three to four and one-half hours and at the same time improve the character of the prints produced and eliminate any possibility of imperfections due to air bubbles, the application of non-uniform pressure, imperfect register or improper drying.

Having described my invention, I claim:

5 An improvement in the art of tri-color pigment printing wherein a sheet supporting a transferable image and a receiving medium to receive the image are brought together in face to face relation to form a "sandwich" and then processed to remove water and air from the sandwich and to effect the transfer of the image to the receiving medium comprising: placing the sandwich on a planar air-impervious supporting surface; placing an airtight flexible blanket over the sandwich to form, in cooperation with the support, a sealed chamber enclosing the sandwich; and evacuating the chamber to withdraw air and moisture from the sandwich and to cause the blanket to press the sandwich uniformly and firmly against the support to effect the transfer of the image.

CHARLES W. WILLIAMS.
